(57) **CLAIM**

The ornamental design for an automobile as shown and described.

DESCRIPTION

FIG. 1 is a front elevation view of a first embodiment of an automobile;

FIG. 2 is a rear elevation view thereof;

FIG. 3 is a left side elevation view thereof;

FIG. 4 is a right side elevation view thereof;

FIG. 5 is a top plan view thereof;

FIG. 6 is a first perspective view thereof;

FIG. 7 is a second perspective view thereof;

FIG. 8 is a front elevation view of a second embodiment of an automobile;

FIG. 9 is a rear elevation view thereof;

FIG. 10 is a left side elevation view thereof;

FIG. 11 is a right side elevation view thereof;

FIG. 12 is a top plan view thereof;

FIG. 13 is a first perspective view thereof; and,

FIG. 14 is a second perspective view thereof.

The bottom views are omitted since they are not easy to see or cannot be seen during usage.

1 Claim, 6 Drawing Sheets
